DESIGN FOR A TABLE

Anthony J. Buckner, New York, N. Y., assignor to Grosfeld House, Inc., New York, N. Y.

Application April 30, 1947, Serial No. 138,704

Term of patent 7 years

(Cl. D33—14)

To all whom it may concern:

Be it known that I, Anthony J. Buckner, a citizen of the United States of America, residing in New York city, county of New York, and State of New York, have invented a new, original, and ornamental Design for a Table, of which the following is a specification, reference being had to the accompanying drawing, forming part thereof, wherein the figure is a front perspective view of a table, showing my new design.

The rear and other end of the table have the same appearance as the front and end shown,

I claim:

The ornamental design for a table, substantially as shown and described.

ANTHONY J. BUCKNER.
